UNITED STATES PATENT OFFICE

CHARLES J. THATCHER, OF NEW YORK, N. Y.

PROCESS OF PURIFYING ANTHRACENE

No Drawing.

Application filed June 16, 1923. Serial No. 645,924.

The invention relates to a process for treating crude anthracene to provide same in refined condition suitable, for example, for the production of anthraquinone by oxidation. 5 Anthracene for this purpose should be of high purity—say from 85% to 95%—and should also be in a very finely divided state. The present invention has for its object a novel process of obtaining anthracene of these 10 characteristics from the crude material, which is usually of 30%, more or less, purity and usually in the form of comparatively large lumps or solid particles of an oily nature.

15 Heretofore, the refining of the anthracene involved either complete solution of the crude anthracene in some suitable solvent, or sublimation of the anthracene, or both. This was necessary because it is not possible to 20 remove substantially all of the impurities from the large solid particles and lumps of crude anthracene thru the agency of solvents for the impurities, because the solvent does not of itself penetrate into the interior of the 25 larger particles to extract all of their impurities therefrom.

In accordance with the present invention, both of the aforesaid essential characteristics of refined anthracene may be economically 30 attained without the trouble and expense of either sublimation or of solution of the anthracene in a solvent.

The following illustrates the novel method of providing refined anthracene from the 35 crude material:—

A suitable quantity of the crude anthracene say of 30% purity, more or less, is treated in a ball or pebble mill—which may be suitably sealed—with a sufficient quantity of 40 solvent for substantially all of the oils and phenanthrene contained in the crude anthracene employed, but which will not appreciably dissolve the anthracene and carbazole. The grinding by the mill is continued for approximately one to two hours or until the 45 anthracene has become very finely pulverized or sub-divided. As a suitable solvent for this purpose either benzol or crude coal tar solvent may be employed, and is mixed with 50 the crude anthracene in the proportion of 500

lbs. of crude anthracene to from 500 lbs. to 1000 lbs. of the solvent.

Other suitable solvents may be used, among which may be mentioned carbon tetrachloride, which is particularly suitable for this 55 purpose where fire hazards are to be strictly avoided, and which may be in the proportion of 500 lbs. to 1000 lbs. to 500 lbs. of the anthracene. Also, mixtures of these or similar solvents may be used for the same purpose. 60

In the selection of solvents for this purpose it is to be borne in mind that the essential characteristic of the invention is the grinding of crude anthracene in a solvent for its oils and in which anthracene itself is relatively insoluble, say to an extent not much exceeding say two parts per hundred of solvent at room temperatures. Enough of the solvent should be used in any case to dissolve substantially all of the oils; and two or more 70 successive treatments with solvent in the proportion indicated may be desirable to this end.

Thru the simultaneous combined grinding and solvent actions, results are attained 75 which were not possible in prior practice or by known methods. By its action, the solvent removes the greasy or oily matters from the crude anthracene, which preclude fine grinding of such material even with water 80 in a ball or pebble mill; and thru the removal of such oily matter, the formation of lumps of anthracene is avoided and the impure anthracene is thus in a state such that it may be quickly broken up by the grinding 85 action into extremely fine particles. It has been found that at the conclusion of the grinding operation, the particles of anthracene appear under the microscope to be no larger than those obtained heretofore only 90 by sublimation. Furthermore, an intimate action of the solvent upon each minute particle of anthracene results thru the grinding of the mixture to microscopic particles, so that substantially all of the said impurities 95 are extracted by the solvent during this grinding action; and which feature is not attained by solvent action alone, as heretofore carried on, on the relatively larger particles of 100 crude anthracene.

At the conclusion of the grinding operation and solvent action, the contents of the mill are to be discharged and filtered. The solvent is then removed by gravity or suction, and the remaining anthracene or residue washed a few times with a small portion of the solvent, or solvents, and dried with recovery of the solvents. The solvent in the filtrate may be recovered as by distillation and utilized for further operation of the process.

By the use of suitably designed apparatus, all of these operations may be performed without substantial loss of even more or less expensive solvents, such as carbon tetrachloride. When distilled, the residue or material remaining in the still consists mainly of oils and phenanthrene which may be readily separated in pure form.

If the process is conducted with anthracene of approximately 30% purity, the foregoing treatment increases the purity of the anthracene to approximately 45%, but the same is now also in a very finely divided state, dry, and suitable for further purification treatments. By suitable selection of the solvent and control of the proportions and conditions of use thereof, as readily understood by workers in the art, substantially no anthracene or carbazole is dissolved by this refining operation, and both of these compounds remain in the resulting partly refined anthracene.

For the removal of the carbazole from the ground and partly refined anthracene, a number of processes are available. For example, the anthracene, now containing from 40% to 50% of carbazole ordinarily, may be treated with a suitable proportion of a solvent therefor, such as acetone or pyridine. One hundred parts of the former dissolves from 6 to 9 parts by weight of carbazole and from $\frac{1}{2}$ to $1\frac{1}{2}$ parts by weight of anthracene at ordinary factory temperatures. The latter solvent at these temperatures will dissolve from 12 to 17 parts by weight of carbazole and from 1 to 2 parts by weight of anthracene; and workers in the art will readily understand from the figures the proper selection of proportions and establishment of conditions for the substantially complete removal of carbazole from the finely divided, partly refined anthracene.

Where it is desirable to avoid the use of inflammable liquids in refining operations for removal of carbazole, the same may be removed by other well-known means such as the nitroso method described in U. S. Letters Patent No. 685,895, or by the well-known fusion with caustic alkali, producing, for example, potassium carbazole and anthracene. The invention, however, is not restricted to any particular method for the separation of the carbazole from the partly refined anthracene. The crude carbazole obtained by any such suitable method, as hereinbefore set

forth, may then be purified to obtain commercially pure carbazole, for example by the method described in my copending application for U. S. Letters Patent Serial No. 522,630, which has eventuated into Patent No. 1,672,630 issued June 5, 1928.

In carrying out the herein-described process for the refining of crude anthracene, anthracene in extremely finely divided condition and of a purity of from 80% to 95% is obtained. Also, the anthracene being in this condition is readily oxidized to anthraquinone without any considerable excess of oxidizing agent.

As has already been noted, there need be no loss either of anthracene or solvent thru the grinding operation, nor in the removal and purification of carbazole, as more particularly set forth in my aforesaid application. The process herein-described effects, therefore, economy in operation and material, rendering it superior to those heretofore described or used for the refining of crude anthracene.

It will be understood, of course, that suitable modifications therein and additions thereto may be made without departing from the spirit of the invention.

For example, the crude anthracene may be ground with a solvent for its oils but which does not dissolve other impurities such as phenanthrene or carbazole in considerable amounts; and these, or similar remaining impurities, may then be readily removed from the now finely ground anthracene by solvents or other treatments hereinbefore specified. Acetone or pyridine may also be used as the solvent with which to grind the crude anthracene, and will dissolve its oils, phenanthrene, carbazole, etc.; and these impurities when so removed can then be separated from one another by well-known methods.

I claim:

1. The process of refining anthracene which includes grinding it in the presence of a solvent for impurities thereof in which the anthracene is relatively insoluble.

2. The process of refining anthracene which includes grinding it, in the presence of a solvent for impurities thereof in which the anthracene is relatively insoluble, for a period of one to two hours.

3. The process of refining anthracene which includes grinding it in the presence of a solvent for its oils in which the anthracene is relatively insoluble.

4. The process of refining anthracene which includes grinding it in the presence of a solvent for its oils in which the anthracene is relatively insoluble, removing the resulting solution, and then separating further impurities from the residue.

5. The process of refining anthracene which includes grinding it in the presence of a solvent for its oils and phenanthrene in which the anthracene is relatively insoluble.

6. The process of refining anthracene which includes grinding it in the presence of a solvent for its oils and phenanthrene in which the anthracene is relatively insoluble, removing the resulting solution, and then separating carbazole from the residue.

7. The process of refining anthracene which includes grinding it in the presence of a quantity of carbon tetrachloride insufficient to dissolve anthracene in proportions relatively large to the impurities dissolved, and removing the resultant solution.

8. The process of refining anthracene which includes grinding one part of anthracene with from one to two parts by weight of carbon tetrachloride, and removing the resultant solution.

9. The process of refining anthracene which includes grinding one part of anthracene with from one to two parts by weight of carbon tetrachloride, filtering the mixture, washing the remaining anthracene with a further portion of the solvent, recovering the solvent and utilizing the same for subsequent operation.

10. The process of refining anthracene which includes grinding one part of anthracene with from one to two parts by weight of carbon tetrachloride, filtering the mixture, washing the remaining anthracene with a further portion of the solvent, distilling off the solvent, and recovering the oils and phenanthrene.

Signed at New York in the county of New York and State of New York this 15th day of June A. D. 1923.
